(57) **CLAIM**

The ornamental design for a hand-held edge de-burrer, as shown and described.

DESCRIPTION

FIG. 1 is a top perspective view showing my new design for a hand-held edge de-burrer;

FIG. 2 is a left side elevational view thereof, wherein the right side elevational view is a mirror image thereof;

FIG. 3 is a top plan view;

FIG. 4 is a bottom plan view; and,

FIG. 5 is a front elevational view thereof, wherein the rear elevational view is a mirror image thereof.
